UNITED STATES PATENT OFFICE.

GEORGE REMNSNIDER, OF BELLEVILLE, ILLINOIS, ASSIGNOR TO IDEAL STENCIL MACHINE CO., OF BELLEVILLE, ILLINOIS, A CORPORATION OF ILLINOIS.

ROTARY FEED FOR STENCIL-MACHINES.

997,583.

Specification of Letters Patent. Patented July 11, 1911.

Application filed September 22, 1910. Serial No. 583,185.

To all whom it may concern:

Be it known that I, GEORGE REMNSNIDER, a citizen of the United States, residing at Belleville, Illinois, have invented a certain 5 new and useful Rotary Feed for Stencil-Machines, of which the following is such a full, clear, and exact description as will enable any one skilled in the art to which it appertains to make and use the same, reference being had to the accompanying drawings, forming part of this specification.

The object of my invention is to provide a feed adjustment for stencil machines by means of which circular stencils such as are 15 used for marking barrel heads and the like may be readily and accurately cut.

In the accompanying drawings which illustrate one form of feeding mechanism made in accordance with my invention together with a portion of a stencil machine to which the same is attached, Figure 1 is a vertical central section; Figs. 2 and 3 are enlarged views showing details of construction; Fig. 4 is a top plan view; Fig. 5 is a 25 diagrammatic view and Fig. 6 is a front elevation partly in section.

Like marks of reference refer to similar parts in the several views in the drawings.

10 represents the stencil cutting machine 30 which need not be shown in detail as it is fully described in another application of even date herewith and same forms no part of the present invention except in combination with the feeding mechanism. Projecting 35 forwardly from the stencil machine 10 are a pair of rails 11 provided on their lower edges with notches 12. Sliding on the rails 11 is a frame 13. This frame 13 is provided with downwardly extending pins 14 carrying 40 a cross bar 15 on which are mounted a pair of rollers 16 adapted to engage with the notches 12 to hold the frame 13 in its different positions nearer to or farther away from the stencil cutting machine 10. The 45 rod 15 is normally held up by means of springs 17 surrounding the pins 14. Carried some distance above the frame 13 is a cross bar 18 which together with the frame 13 forms a yoke, as best seen in Fig. 6. Arranged between the cross bar 18 and the 50 frame 13 is a rotary member 19 supported by ball bearings 20 as best shown in Fig. 1.

This rotary member 19 is adapted to support the stencil sheet 21 which is clamped thereto by means of a clamping plate 22. 55 The clamping plate 22 is carried on a spindle 23 passing through the center of the sleeve 24, rotatably mounted in the bar 18. The clamping plate 22 is normally held against the member 19 by means of coil 60 springs 25 surrounding pins 26 which enter openings in the clamping plate 22 and are rigidly secured in a gear wheel 27 carried on the lower end of the sleeve 24. The upper end of the spindle 23 is provided with 65 a head 28 by means of which the clamping plate may be raised out of contact with the member 19.

Projecting forwardly from the cross bar 18 is a bracket 29 in which is mounted a 70 spindle 30. On the lower end of this spindle 30 is a gear wheel 31 meshing with the gear wheel 27. Rigidly secured to the spindle 30 directly above the bracket 29 is a hand-wheel 32 by means of which the said 75 spindle may be rotated. Rigidly secured to the spindle 30, above the hand-wheel 32 is a hollow rotary member 33. Loosely mounted on the spindle 30 within the hollow member 33 is a block 34 carrying a 80 pivoted member 35 held against the inner periphery of the member 33 by means of a spring 36. This pivoted member 35 acts as a friction clutch so that when oscillating motion is imparted to the member 34 an intermittent rotary motion will be imparted to the member 33. The member 34 is provided at its upper face with a pair of lugs 37 having openings through which passes a rod 38 which is driven from the operating 85 means of the stencil machine. The pivoted member 35 is provided near its outer end with an upwardly projecting pin 39 by means of which the said member may be held out of contact with the member 33 so 90 as to allow the spindle 30 to be removed in either direction by means of the hand-wheel 32.

In order to drive the rod 38 from the stencil cutting machine I secure to the spindle 100 40 an arm 41 shown in detail in Fig. 2. This arm 41 is held on the spindle 40 by means of a set screw 42. It will be understood that the spindle 40 is given a rocking

motion by means of the operating handle 43 of the stencil machine. The upper end of the arm 41 engages with the bifurcated end 44 of an L-shaped member 45 which is slidably mounted upon the rod 46 carried by the stencil machine 10. The L-shaped member 45 is provided on its upper face with an opening for receiving the short down-turned end 47 of the rod 38. 10 In order to prevent the tipping of the L-shaped member 45 on the rod 46 I provide the upper end of the arm 41 with a washer 48 held in place by means of a screw 49, as shown in Fig. 1. In order to move the 15 frame 13 toward and away from the stencil cutting machine, the bracket 29 is provided with a handle 50.

The operation of my mechanism is as follows: In order to insert the stencil sheet 20 21 the clamping plate 22 is drawn out of contact with the rotary member 19 by means of the head 28. The stencil sheet may then be slipped in position and the head 28 released so that the springs 25 will firmly 25 clamp the stencil sheet 21 between the rotary member 19 and the clamping plate 22. When the stencil cutting mechanism is operated by means of the handle 43 to cut the character in the sheet, the spindle 40 will 30 be rocked so that the arm 41 will impart sliding motion to the L-shaped member 45. This will move the rod 38 as is shown by dotted lines in Fig. 5, thus imparting an 35 oscillating movement to the member 34. By means of the friction clutch 35 which acts substantially in the same manner as a ratchet this will impart a rotary movement to the member 33 and consequently to the spindle 30 on which the said member 33 is rigidly 40 mounted. The rotation of the spindle 30 will be communicated by means of the gears 31 and 27 to the clamping plate 22 so that the stencil sheet 21 will be moved forward in position to cut the next letter. When the 45 frame 13 is moved nearer to the stencil cutting mechanism the rod 38 will slide in the lugs 37 and an equal amount of movement of the sliding member 45 will move the member 34 through a greater angle as is 50 illustrated by the diagram Fig. 5. At the same time the travel at the point 47 will remain uniform. As this point 47 is substantially directly over the feed of the base of the letters the feed at the base of the letters 55 will be substantially the same when cutting different sizes of circles. As will be seen from Fig. 5, the member 35 as well as the member 34 travels through different arcs when the frame 13 is in its different positions and consequently it is not practical to use a toothed ratchet for the purpose of changing the oscillating movement of the member 34 into a rotary movement. When it is desired to move the stencil sheet through 60 a greater distance than the normal feed

the member 35 may be moved out of contact with the member 33 by means of the pin 39 and the stencil sheet rotated by means of the hand-wheel 32.

Having fully described my invention, 70 what I claim as new and desire to secure by Letters Patent of the United States, is:

1. The combination with stencil cutting mechanism, of a rotary clamping device for the stencil sheet, said stencil cutting mechanism being adapted to be positioned independently of said clamping device, means for actuating the stencil cutting mechanism to cut, and connections between said actuating means and clamping device for rotating 75 the latter.

2. The combination with stencil cutting mechanism, of a rotary clamping device for the stencil sheet, a spindle arranged adjacent to said clamping device and operatively 85 connected therewith, means for operating said stencil cutting mechanism, and operating connections between said stencil cutting mechanism and spindle for operating the latter.

3. The combination with stencil cutting mechanism, of a rotary clamping device for the stencil sheet, said clamping device being movable toward and away from said stencil cutting mechanism, and connections between 95 said stencil cutting mechanism and said clamping device for operating the latter from the former.

4. The combination with stencil cutting mechanism, of a rotary clamping device for 100 the stencil sheet, said clamping device being movable toward and away from said stencil cutting mechanism, and a sliding connection between said stencil cutting mechanism and said clamping device for operating the latter from the former.

5. The combination with stencil cutting mechanism, of a rotary clamping device for the stencil sheet, a spindle for operating said clamping device, an oscillating member, connections between said oscillating member and spindle for transmitting rotary motion to the latter, and connections between said stencil cutting mechanism and said oscillating member.

6. The combination with stencil cutting mechanism, of a rotary clamping device for the stencil sheet, said clamping device being movable toward and away from said stencil cutting mechanism, a spindle for operating said clamping device, an oscillating member, connections between said oscillating member and spindle for transmitting rotary motion to the latter, and sliding connections between said stencil cutting mechanism and said oscillating member.

7. The combination with stencil cutting mechanism, of a rotary clamping device for the stencil sheet, a spindle for operating said clamping device, an oscillating member, a

- friction clutch between said oscillating member and said spindle for transmitting rotary motion to the latter, and connections between said stencil cutting mechanism and 5 said oscillating member.
8. The combination with stencil cutting mechanism, of a rotary clamping device for the stencil sheet, said clamping device being movable toward and away from said stencil cutting mechanism, a spindle for operating said clamping device, an oscillating member, a friction clutch connecting said oscillating member to said spindle for transmitting rotary motion to the latter, and sliding connections between said stencil cutting mechanism and said oscillating member. 10
9. The combination with stencil cutting mechanism, of a frame movable toward and away from said stencil cutting mechanism, a rotary clamping device for the stencil sheet carried by said frame, a spindle carried by said frame and geared to said clamping device, an oscillating member, connections between said oscillating member and spindle 15 for transmitting rotary motion to the latter, and connections between said stencil cutting mechanism and said oscillating member.
10. The combination with stencil cutting mechanism, of a frame movable toward and away from said stencil cutting mechanism, a rotary clamping device for the stencil sheet carried by said frame, a spindle carried by said frame and geared to said clamping device, an oscillating member, a friction clutch 20 between said oscillating member and spindle for transmitting rotary motion to the latter, and sliding connections between said stencil cutting mechanism and said oscillating member. 25
11. The combination with stencil cutting mechanism, of a frame movable toward and away from said stencil cutting mechanism, a rotary member supported on said frame by anti-friction bearings, a clamping 30 plate coöperating with said rotary member to clamp the stencil sheet, and operating connections between said clamping plate and stencil cutting mechanism. 35
12. The combination with stencil cutting mechanism, of a frame movable toward and away from said stencil cutting mechanism, a rotary member supported on said frame by anti-friction bearings, a spring actuated clamping plate coöperating with said rotary member to clamp the stencil sheet, and operative connections between said clamping plate and said stencil cutting machine. 40
13. The combination with stencil cutting mechanism, of a frame movable toward and away from said stencil cutting mechanism, a rotary member supported on said frame by anti-friction bearings, a spring actuated clamping plate coöperating with said rotary member to clamp the stencil sheet, a spindle mounted adjacent to said clamping plate, 45 gearing connecting said spindle and clamping plate, and operating connections between said clamping plate and stencil cutting mechanism.
14. The combination with stencil cutting mechanism, of a frame movable toward and away from said stencil cutting mechanism, a rotary member supported on said frame by anti-friction bearings, a spring actuated clamping plate coöperating with said 50 rotary member to clamp the stencil sheets, a spindle carried by said frame adjacent to said clamping plate, gearing connecting said spindle and clamping plate, an oscillating member, a friction clutch between said oscillating member and spindle for transmitting rotary motion to the latter, and a sliding connection between said oscillating member and said stencil cutting mechanism. 55
- In testimony whereof, I have hereunto set 55 my hand and affixed my seal in the presence of the two subscribing witnesses.
